SWAGING MACHINE

Joseph M. Root, Detroit, Mich., assignor to Harold C. Johns, Virginia Johns, Walter E. Davison, and Leona Davison, copartners, doing business as Park Manufacturing Company, Detroit, Mich.

Application March 20, 1944, Serial No. 527,313

8 Claims.

(Cl. 78—21)

The invention relates to swaging machines and more particularly to machines for reducing the diameter of members of circular cross section. As a specific instance, a socket member having an insert therein may be swaged to contract the socket upon the insert thereby securing these members to each other.

It is the object of the invention to obtain a construction with which successive pieces of work may be easily inserted and withdrawn and which rapidly performs the swaging operation thereupon. To this end the invention consists in the construction as hereinafter set forth.

In the drawings:

Fig. 1 is a side elevation of the machine;
Fig. 2 is a horizontal section on line 2—2,
Fig. 3;

Fig. 3 is a front elevation;

Fig. 4 is a similar view with the front closure withdrawn;

Fig. 5 is a similar view with the stop plate removed;

Fig. 6 is a section on line 6—6, Fig. 2;

Fig. 7 is a view similar to Fig. 2 showing the parts adjusted for operation;

Fig. 8 is a section on line 8—8, Fig. 6;

Fig. 9 is a sectional elevation showing a socket and an insert to be placed therein; and

Fig. 10 shows these parts in engagement with each other and the swaging dies.

As shown in Fig. 1, A is a suitable frame having a horizontally extending race member or bearing B at the upper end thereof for receiving a rotary member C. A motor D is mounted on the base of the frame and a pulley and belt drive connection E connects the motor with the rotary member C. At the opposite end of the bearing B is an enlarged circular recess B' for receiving a head C' on the rotary member C. This head has a forward portion C² of smaller diameter leaving between the same and the wall of the recess B' an annular space for receiving a series of rollers F and an annular cage member G in which said rollers are mounted. The forward portion C² of the head C' is transversely slotted to form parallel guide bearing C³. Between these guide bearings and on opposite sides of the axis of the member C are swaging die blocks H which are radially movable and are actuated by hammer members I that, in turn, are actuated by the rollers F as will be hereinafter explained. The cage member G has spaced pockets therein opened at the inner end for the axial engagement of the rollers F therewith. After the rollers F are assembled with the cage member G, the inner ends of the pockets are

then closed by a ring bearing G' secured to the cage member G by screws G². The opposite outer end of the cage member G has a plurality of radial slots G³ therein in which are located pivoted dogs J. These dogs are adapted to couple the cage rotary member G with the member C and to this end the latter member is provided with an annular member K secured to the outer end of the portion C² by screws K'. The annular member K has radially projecting segments K² forming shoulders K³ in the path of the dogs J in one position of the latter, while in another position said dogs will clear said shoulders. At the front of the bearing B is a removable closure L. Preferably, the mounting for the closure L comprises lugs L' projecting outward from the member B, and arms L² extending oppositely from said member L and having bifurcated portions L³ straddling said lugs L' and having connecting pins L⁴. Thus, by removing one of said pins L³ the closure L may be swung outward on the other pin forming a hinge so as to clear the recess B'. The closure L is formed with a central inwardly tapering opening L⁸ through which the work may be introduced into operative relation to the swaging die blocks H. The closure L is also provided with annular bearing members L⁴ and L⁵, the former being within the annular member K and fastened by screws L¹⁰ to the closure L and the latter being attached to the closure at the outer end of the cage member G. Surrounding the closure L is an axially adjustable ring M for engaging the outer ends of the dogs J to actuate the same. This ring M is secured to the closure L by pins M' projecting inward from the ring and engaging inclined slots M² in the closure L so that a slight rotary adjustment of the ring will cause a simultaneous axial movement thereof. A handle M³ projecting radially from the ring M forms a means for adjusting the same. Each of the dogs J has mounted, on its outer end portion a wheel or roller J' which forms an antifriction bearing on the inner face of the ring M. The wheels J' are yieldably pressed against said ring by plungers J² and springs J³ engaging bores in the cage member G. The outer ends of these plungers J² engage the outer end portions of the dogs J. Thus, when the ring M is at the outer end of its axial movement, the springs J³ and plungers J² will move the dogs J into the path of the shoulders K³ to couple the cage G with the rotary member C. On the other hand, when the ring M is moved axially inward, it will swing the dogs J into a position to clear said shoulders K³ and thus uncouple the cage G from the rotary member C.

Operation

When the motor D is energized, rotary motion will be imparted to the rotary member C and all the elements attached thereto. Assuming that the ring M is in a position to couple the cage member G to the portion C², then this cage member G and the rollers F therein will also revolve with the rotary member C and at the same angular speed. Furthermore, centrifugal force developed by the rotation of the swaging die blocks H and actuating hammer members I will move these parts radially outward so as to separate the die blocks H from each other for the introduction of work therebetween. The amount of separation is increased by the engagement of the outer ends of the hammer members I with recesses I' in the cage member G at substantially diametrically opposite points thereof, said recesses I' being in registration with said hammer members I when the dogs J are in contact with the shoulders K³. In this position of the parts, the work such as a socket member N surrounding an insert O, is moved through the opening L⁸ in the closure L into the space between the die blocks H. There is also preferably provided a work holder P for properly centralizing and positioning the work. This holder, as shown in Fig. 2, comprises a socket member P' slideable within a cylindrical member P² which also contains a spring P³ and has a closure cap P⁴. All of these parts are inserted within an axial recess P⁵ in the member C, and the arrangement is such that a projecting end portion N' of the work socket member N may be inserted within the socket holder P' and pressed inward against the tension of the spring P³. This arrangement will cause the socket member N to be positioned properly between the die blocks H for the swaging operation. To accomplish the latter the operator taking hold of the handle M³ rotates the ring M to simultaneously move the same axially thereby disengaging the dogs J from the shoulders K³. This permits frictional resistance afforded by the engagement of the rollers F with the race member or bearing B and the hammer members I to retard the rotation of the cage G to a slower angular speed than that of the rotary member C so that the rollers F will successively impinge against the hammer members I to actuate the same radially inward. The hammer members I, in turn, will actuate the die blocks H which will deliver a succession of blows against the outer surface of the socket N swaging the same into binding contact with the insert O. The operation is so rapid that the swaging is accomplished in a short interval of time after which the ring M is returned by the handle M³ to its normal position so that the dogs J will be moved into the path of the shoulders K³ to again couple the cage G with the rotary member C. The completed work may then be removed, new work introduced and the operation repeated.

The work to be swaged may vary in dimensions which necessitates changing the swaging die blocks H. This may be easily performed by removing one of the pins L³ and swinging the closure L outward to provide clearance for the removal of the die blocks H and the insertion of exchange die blocks H. To avoid interference by the annular member K, the latter is provided with notches K⁴ in its inner periphery which permit passage therethrough of the corners of the die blocks H. It is, therefore, possible to quickly exchange die blocks whenever there is a change in dimensions of the work to be swaged.

What I claim as my invention is:

1. In a swaging machine, a rotating member having a transversely extending guideway thereon, swaging members slideable on said guideway on the opposite sides of the axis of rotation and movable radially outward from said axis by centrifugal action to form therebetween a space for receiving the work, a surrounding race member spaced from and concentric with said rotating member, an annular member in the space between said rotating member and race member provided with a series of spaced rounded inward projections, coupling means between said rotating member and annular member for causing the same to rotate at the same angular speed, and means operable during the rotation of said members for uncoupling said coupling means whereby said annular member will be frictionally retarded and the inward projections thereof will successively actuate said swaging members radially inward to swage the work therebetween.

2. In a swaging machine, a rotating member having a transversely extending guideway, swaging members slideable on said guideway on the opposite sides of the axis of rotation and movable radially outward from said axis by centrifugal action to form therebetween a space for receiving the work, a surrounding race member spaced from and concentric with said rotating member, a series of rollers in the space between said rotating member and race member, a cage for said rollers also in said space, coupling means between said rotating member and cage member for causing the same to rotate at the same angular speed, and means operable during the rotation of said members for uncoupling said coupling means whereby said rollers and cage will travel about said race member at an angular speed less than that of said rotating member, and said rollers will successively impinge upon said swaging members actuating the same radially inward to swage the work therebetween.

3. In a swaging machine, a rotating member having a transverse slot therein forming a guideway, swaging members slideable in said guideway on opposite sides of the axis of rotation and movable radially outward from said axis by centrifugal action to form a space therebetween for the reception of the work, a bearing in which said rotating member is journaled having an enlarged recess forming a raceway surrounding and spaced from said guideway, a series of rollers and a cage therefor located in the space between said guideway and said raceway, coupling means between said rotating member and cage for causing the same to rotate at the same angular speed, and means operable during the rotation of said members for uncoupling and coupling said coupling means whereby said cage when uncoupled and said rollers will travel around said raceway at an angular speed less than that of said rotating member and said rollers will successively impinge upon said swaging members actuating the same radially inward to swage the work therebetween.

4. In a swaging machine, a rotating member having a transverse slot therein forming a guideway, exchangeable die members and actuating members therefor slideable in said guideway on opposite sides of the axis of rotation but movable radially outward from said axis by centrifugal action to form a space between said die members for receiving the work, a bearing in which said rotating member is journaled having an enlarged recess forming a raceway surrounding and

spaced from said guideway, a series of rollers and a cage therefor located in the space between said guideway and raceway, said cage having pockets between the rollers for engaging and limiting the outward movement of said actuating members, dogs for coupling said rotating member and cage member in the relative positions thereof when said actuating members are engaged with said pockets thereby causing said members to rotate at the same angular speed, and means operable during the rotation of said parts for moving said dogs out of coupling engagement whereby said rollers are permitted to travel about said raceway in rolling contact therewith at a speed less than that of said rotating member thereby causing said rollers to successively impinge against said actuating members to move said die members radially inward and to swage the work therebetween.

5. In a swaging machine, a rotating member having a transverse slot therein forming a guideway, swaging die members and actuating members therefor in said guideway on the opposite sides of the axis of rotation and movable radially outward from said axis by centrifugal action to form therebetween a space for receiving the work, a surrounding race member spaced from and concentric with said rotating member, a series of rollers and a cage therefor in the space between said rotating member and race member, said cage having pockets therein between said rollers for receiving and limiting the outward movement of said actuating members, dogs on said cage for engaging shoulders on said rotating member to effect a coupling engagement therebetween and to drive said cage at the same angular speed as said rotating member, a non-rotating member in front of said rotating members centrally apertured for the passage of the work therethrough, an annular member rotatively mounted on said non-rotatable member with a connection therebetween for causing an axial movement of said annular member upon rotative adjustment thereof, said annular member having an antifriction bearing on said dogs whereby the axial movement thereof will disengage the coupling permitting the rollers to travel around said raceway at an angular speed less than that of said rotating member thereby successively impinging upon said actuating members to move said die members radially inward and to swage the work therebetween, and means for automatically restoring said dogs to coupling position when said annular member is axially withdrawn therefrom.

6. In a swaging machine, a rotating member having a transverse slot therein forming a guideway, exchangeable swaging die members and actuating members therefor slideable in said guideway on opposite sides of the axis of rotation and movable radially outward from said axis by

5 centrifugal action to form between said die members a space for receiving the work, a bearing in which said rotating member is journaled having an enlarged recess forming a raceway surrounding and spaced from said guideway, a series of rollers, and a cage therefor located in the space between said rotating member and raceway, a centrally apertured closure for said recess removably connected to said bearing serving to 10 normally retain said die members and actuating members against disengagement from said guideway but permitting exchange of die members when desired, dogs pivotally mounted on said race member for engaging shoulders on said rotating member to cause both members to rotate at the same angular speed, means for yieldably holding said dogs in coupling position, an annular member rotatively adjustable on said closure member and provided with means for causing an axial movement upon rotative adjustment thereof, and roller bearings on said dogs for engaging said annular member whereby an axial movement of the latter will disengage said dogs and permit said cage and rollers to travel at a slower angular speed than said rotating member for 15 the purpose described.

7. In a swaging machine, a rotating member having a transversely extending guideway thereon, swaging members slideable on said guideway on the opposite sides of the axis of rotation and movable radially outward from said axis by centrifugal action to form therebetween a space for receiving the work, an annular member surrounding said rotating member and normally rotating therewith at the same speed, said annular member having a series of spaced inward projections, and means for retarding the rotation of said annular member to cause said inward projections to successively impinge on said swaging members and to move the same inward against the work.

8. In a swaging machine, a rotating member having a transversely extending guideway thereon, swaging members slideable on said guideway on the opposite sides of the axis of rotation and movable radially outward from said axis by centrifugal action to form therebetween a space for receiving the work, an annular member surrounding said rotating member having a series 45 of spaced inward projections, coupling means between said rotating member and annular member for causing the same to rotate at the same angular speed, means operable during the rotation of said members for uncoupling said coupling means, and means for retarding the rotation of said annular member when uncoupled from said rotating member whereby said inward projections successively impinge against said swaging members to move the same inward 50 against the work.

JOSEPH M. ROOT.
